UNITED STATES PATENT OFFICE.

WILLIAM W. RIDDELL, OF CHICAGO, ILLINOIS.

VALVE.

1,240,879.

Specification of Letters Patent. Patented Sept. 25, 1917.

Application filed January 12, 1917. Serial No. 142,071.

To all whom it may concern:

Be it known that I, WILLIAM W. RIDDELL, a citizen of the United States, residing at Chicago, in the county of Cook and State of Illinois, have invented new and useful Improvements in Valves, of which the following is a specification.

This invention relates to internal combustion engines having a rotary valve governing the admission of the fuel charges.

The invention has for its object to provide a novel and improved means for cooling the valve by air, and for feeding the air passing through the valve to the carbureter or other charge-forming device of the engine, the latter being therefore supplied with warm air to facilitate the vaporization of the liquid fuel.

The invention also has for its object to deliver water vapors to the carbureter by means of a connection between the radiator and the air passage through the valve as will be described hereinafter in detail.

In order that the invention may be better understood, reference is had to the accompanying drawings forming a part of this specification.

In the drawings,

Figure 1 is an elevation of the engine 30 equipped with my improved valve mechanism;

Fig. 2 is a longitudinal section thereof;

Fig. 3 is an elevation of the rotary valve removed;

35 Figs. 4 and 5 are enlarged cross-sections on the lines 4-4 and 5-5, respectively, of Fig. 2, and

Fig. 6 is a sectional detail of a vapor-feeding means.

40 Referring specifically to the drawings, the invention is shown applied to an engine having four cylinders 10 in each of which a piston 10^a reciprocates. The cylinders may be cast *en bloc* as is the usual practice, and they 45 are closed at their top or inner end by a head 11. In the contiguous portions of the cylinders and the head is a longitudinal bore in which is mounted a rotary valve 12 governing the admission of the fuel charges.

50 In order to provide for the lubrication of the valve 12, its outer surface is provided with longitudinal grooves 12^a, and over each cylinder, the head 11 has a lubricant inlet 11^a leading to the bore in which the valve 55 works.

In the side of the cylinders are fuel inlet passages 13 which open at their outer ends into an intake manifold 14 having a connection 15 with a carbureter or other charge-forming device 16. The other ends of the 60 passages open into the bore in which the valve 12 seats, the latter having cavities 17 in its side so located as to register with the inner ends of the passages 13 and thus establish communication between the latter 65 and inlet ports 18 in the top of the cylinders 10, to admit the fuel charged to the latter.

The valve 12 is hollow and open at both ends, whereby an air chamber or passageway 19 is formed in the valve, said chamber extending throughout the entire length of the valve. Into one end of this chamber extends a pipe 20 leading to the air intake of the carbureter 16. On the other end of the valve is fixed a sprocket wheel 21 to provide a 75 driving connection for the valve. Any suitable gearing may be provided for rotating the valve from the engine shaft at a fixed ratio of transmission according to the cycle of the engine. If the engine is a four-cycle 80 engine, a two-to-one gearing will of course be provided.

When the engine is in operation, the suction in the air-intake of the carbureter, draws air through the valve chamber 19 85 and the valve 12 is thus cooled. A large radiation surface is provided by forming the wall of the chamber 19 with fins 19^a. The air in its passage through the valve absorbs heat, and the carbureter therefore draws in 90 warm air which facilitates the vaporization of the liquid fuel.

To the air inlet end of the valve chamber 19 is connected a means for delivering water vapor to said chamber, said means comprising the following parts:

At 22 is shown a fragment of the radiator in which the water which circulates through the water jacket of the engine is cooled. In the filler neck 22^a of the radiator is mounted a tube 23 which passes out of the radiator and extends into the air inlet end of the valve chamber 19. That portion of the tube 23 which is located in the filler neck of the radiator is arranged perpendicularly thereto and its upper end is open and terminates close to the outer end of the neck, said neck being provided with the usual closure in the form of a screw cap 24. The inlet end of the tube 23 is above the normal water level 105 110

in the radiator, and the vapors rising from the heated water in the radiator pass into said tube and are carried by the same into the valve chamber 19, through which latter 5 they pass and are drawn through the pipe 20 to the carbureter 16. The carbureter is therefore supplied with vapor-laden heated air, which produces a better fuel mixture and also reduces carbonization to a mini- 10 mum.

In order that the vapor delivery tube 23 may have a continuous supply of air, the radiator cap 24 is provided with an aperture from which a tube 25 depends through 15 the neck 22^a into the top water chamber of the radiator. In this tube is loosely mounted a rigid stem 26 rising from a float valve 27. Normally, this valve rests on the bottom of the top water chamber of the radiator, or floats on the surface of the water as 20 it rises in said chamber. If the water level rises beyond a predetermined limit, the valve rises and closes the tube 25 by seating against the inner bottom end thereof as 25 shown dotted in Fig. 6, thereby preventing water from splashing out through the tube 25 and over the cap 24. The suction in the

tube 23 is strong enough to draw air into the same through the water.

I claim:

1. The combination with a water-cooled internal-combustion engine having a port, a charge-forming device, and a radiator for the cooling system; of a rotary valve for the aforesaid port, said valve having an air passageway the outlet of which is connected to the air-intake of the charge-forming device, and means for delivering water vapor from the aforesaid radiator to the air passageway.

2. The combination with a water-cooled internal-combustion engine having a port, a charge-forming device, and a radiator for the cooling system; of a rotary valve for the aforesaid port, said valve having an air passageway the outlet of which is connected to the air-intake of the charge-forming device, and a water vapor delivering conduit extending into the air passageway and connected to the radiator above the water level 50 therein to obtain a supply of water vapor therefrom.

In testimony whereof I affix my signature.

WILLIAM W. RIDDELL.
